TOILET SIGNAL DEVICE

Alfred H. Simonsen, Chicago, Ill.

Application October 20, 1936, Serial No. 106,595

11 Claims. (Cl. 4—239)

This invention relates to toilet signal devices and more particularly to signal appliances for attachment to toilet seats, although certain features thereof may be employed with equal advantage for other purposes.

It contemplates more especially the provision of a signal device for association with a toilet seat that will indicate the functional performance thereof by infants, invalids or other incapacitated individuals.

Numerous types of signal devices have heretofore been proposed for different purposes, and attempts have been made to signalize the toilet functions of infants and invalids so far as indicating when a mattress has become wetted and for analogous purposes. It is proposed, however, to provide a practical, inexpensive, and effective device to avoid the necessity of constant attendance and supervision to the toilet functions of infants, invalids and other incapacitated individuals.

Extreme patience is normally required in exerting supervisory and attendant efforts to effect the toilet functions of infants, invalids and other incapacitated individuals. Then, too, such requires appreciable time from the moment a desire is expressed or from the time the attendant deems it necessary to urge such a function. Infants, invalids and incapacitated individuals delay such action and usually demand coaxing to an extent that such occupies a greater part of an attendant's time.

With the teachings of the present invention, the infant, invalid or incapacitated individual can be placed by an attendant over a toilet seat and allowed to remain thereover without further attention. When the toilet has taken place, a signal will be automatically operated and will serve as an indicator for the attendant to dispose of the excrement and return the infant, invalid or other incapacitated individual to their normal routine without the attendant having devoted any appreciable time. Then, too, it is proposed as an optional feature, to provide a signal that is pleasing such as the operation of a music box so as to induce the performance or accomplishment of the normal toilet functions.

One object of the present invention is to simplify the construction and improve the operation of devices of the character mentioned.

Another object is to provide an improved and simplified toilet signal device that will more effectively indicate the functional performance thereof.

Still another object is to provide a signal de-

vice for the toilet that will indicate the normal discharge of excrement to the receptacle from the position above the seat member.

A further object is to provide a simple, inexpensive, and more effective signal device for a toilet receptacle that will be operative responsive to the discharge of excrement to the toilet receptacle from a position above the seat member thereof.

A still further object is to provide an attachment for a toilet seat so as to provide signal operating means responsive to the discharge of excrement to the receptacle from a position above the seat member.

Still a further object is to provide a simple and improved bracket member having signal means thereon for ready attachment to a toilet seat that is operative responsive to the discharge of excrement to the receptacle of a toilet.

Other objects and advantages will appear from the following description of an illustrative embodiment of the present invention.

In the drawing:

Figure 1 is a perspective view of a device embodying features of the present invention, the dotted outline showing a toilet seat member to which attachment may be effected to utilize the teachings of the present invention.

Figure 2 is a sectional plan view of the signal device shown in Figure 1, the casing being shown in section along the horizontal plane to clarify the showing and disclose the internal mechanism.

Figure 3 is a perspective view of a modified form of the device shown in Figure 1, it being adapted for male use rather than female use as shown in Figure 1.

Figure 4 is a sectional view in elevation of the device shown in Figure 3.

The structure selected for illustration comprises a toilet seat 10 of any desired shape or configuration depending upon the use for which it is designed. In the preferred embodiment, the seat member 10 is divided along the front portion thereof to present an opening 10^a, although this is not a requirement and depends upon the dictates of commercial practice. A signal device is preferably attached to the toilet seat 10, and in this instance comprises a casing 11 having a detachable closure 11^a on the underside thereof. This signal device is purposed to indicate the performance of the toilet by an infant, invalid or other incapacitated individual as will appear more fully hereinafter.

The detachable closure 11^a is provided with bracket arms 11^b which are integrally or other-

wise attached thereto to secure the housing 11 to the seat 10 through the medium of its closure 11^a. Any suitable fastening expedients may be inserted through the apertures provided in the brackets 11^b to effectively anchor the housing 11 with its closure plate 11^b to the seat member 10.

In the present embodiment, the housing 11 is attached to the seat member 10 within the opening 10^a provided therein; however, it may be detachably associated with any other portion of the seat 10 depending upon the dictates of commercial practice and the requirements for any particular use by infants, invalids or other incapacitated individuals.

As shown, the housing 11 terminates, in this instance, in a depending plate 11^c disposed inwardly of the seat member 10 to sustain instrumentalities which will be more clearly described hereinafter. To this end, the depending plate 11^c is provided, in this instance, with a pair of angle brackets 12 fixed to the downward extremity of the plate 11^c so as to provide a horizontal pivot 13 for the lever 14.

The lever 14 has a downwardly offset arm 14^a which terminates in a horizontally extended arm 14^b serving to sustain an excrement indicator such as a disk 15 disposed in the path of the normal discharge of the excrement from a position above the seat member 10. The disk 15 is preferably somewhat concave in configuration and is preferably stamped or otherwise shaped from sheet metal for attachment to the horizontal terminus 14^b of the lever extension 14^a, thereby disposing the disk 15 appreciably within the confines of the seat member 10 for adaptation to any normal excrement discharge by infants, invalids, or other incapacitated individuals to the end of requiring attention in their excrement functions.

It is to be noted that the lever 14 has an upwardly extending arm 16 forwardly of the plate 11^c, it having a horizontally extending extremity or detent 17 that enters the housing 11 (Figure 2). As shown, the detent 17 is disposed in the path of a rotary member 18 constituting a part of a spring motor 19 mounted in the housing 11. The motor 19 operates a signal 20 to actuate a music producing element 21 that constitutes, in this instance, an audible indicator that is attachable to a device of this character, although any other type of indicator may be employed with equal or even better advantage should commercial practice so dictate.

In order to render the motor 19 operable a spring winding knob 22 extends exteriorly of the housing 11 for operative connection to the spring of the motor 19. It is to be noted that the lever 14 is mounted on the pivot 13 at a point so as to normally gravitate the lever with its excrement disk 15 in a clockwise direction (viewed from Figure 1) so as to dispose the detent 17 in the path of the rotor 18, thereby precluding the operation of the spring motor 19. With the discharge of excrement to the disk 15 that is disposed in the path thereof, the lever 14 will be moved in a counter-clockwise direction (viewed from Figure 1) to raise the detent 17 beyond the path of the rotor 18, thereby releasing the spring motor 19 to operate the music element 21.

The lever 14 is so balanced that even the slightest deposit of excrement upon the disk 15 by the infant, invalid, or other incapacitated individual disposed over or upon the seat member 10, will release the spring motor 19 and emit the musical audible signal to inform the attendant that the

toilet has taken place. This avoids the constant supervision of the attendant, and the infant, invalid or other incapacitated individual may be left in any possible posture above the seat member 10 and the signal will be operated responsive to the normal performance of the toilet function.

It may be desirable to provide a somewhat modified structure for male individuals, since it would be preferable in such instances to substitute a splash guard 22 (Figure 3) in lieu of the depending plate 11^c (Figure 1) so as to constitute an integral part of the housing 11. The splash guard 22 would then support a collector 18^a in the path of the normal excrement discharge and for that purpose brackets 23 are provided to pivotally support the collector 18^a that preferably though not essentially has the bottom thereof in a slightly rearward inclined position. With this arrangement, the collector would be pivoted in a counter-clockwise direction (viewed from Figure 20 4), thereby releasing the detent 17 from the rotor 18 comprising a part of the spring motor 19.

In all of the structures described supra, it may be preferable to provide the angle brackets 12 (Figure 1) with a depending bracket 24 to sustain a resilient buffer 25 that projects beyond the disk or receptacle 15, thereby serving to support the entire seat member 10 in the proper position from a wall hook without injury to the signal mechanism described herein.

In the embodiment disclosed in Figure 3, the buffer 25 may be provided on the bracket 23 that also serves to support the collector 18^a. In any event, there usually will be a waste container or receptacle disposed beneath the seat member 10 to collect the excrement discharge thereto. The structure described herein to illustrate the teachings of the instant invention may be built into the seat member 10 or constitute a separate bracket for ready association to seat members already in existence, and the type of signal may be varied within a wide range depending upon the dictates of commercial practice.

Various changes may be made in the embodiment of the invention herein specifically described without departing from or sacrificing any of the advantages of the invention or any features thereof, and nothing herein shall be construed as limitations upon the invention, its concept or structural embodiment as to the whole or any part thereof except as defined in the appended claims.

I claim:

1. An infant's toilet appliance comprising an attachment for a toilet seat containing a signal device, an actuator for the signal device extending into the toilet zone, and weight-responsive means carried by the actuator and operative to control the same.

2. An infant's toilet appliance comprising an attachment for a toilet seat containing a signal device, an extension from the latter into the toilet zone, a rockable lever adapted to actuate the signal with one end, and a receptacle carried by the other end of the lever and effective when weighted to rock the lever and actuate the signal.

3. An infant's toilet appliance comprising an attachment for a toilet seat, said seat being divided at its front portion to form an opening, a signal device positioned in said opening, an extension from the signal device extending into the toilet zone, a rockable lever adapted to actuate the signal with one end, and a receptacle carried by the other end of the lever and effective when weighted to rock the lever and actuate the signal.

4. An infant's toilet appliance comprising an attachment for a toilet seat, said seat being divided at its front portion to form an opening, a signal device positioned in said opening, and said signal device having lateral extending portions adapted to be secured to the under side of said seat and an extension from the signal device extending into the toilet zone, a rockable lever adapted to actuate the signal with one end, and a receptacle carried by the other end of the lever and effective when weighted to rock the lever and actuate the signal. 5
5. An infant's toilet appliance comprising an attachment for a toilet seat containing a signal device, a casing for housing said signal device, an extension being a continuation of the rear wall of said casing extending into the toilet zone, a rockable lever adapted to actuate the signal with one end, and a receptacle carried by the other 10 end of the lever and effective when weighted to rock the lever and actuate the signal. 15
6. An infant's toilet appliance comprising an attachment for a toilet seat containing a signal device, an extension from the latter into the toilet zone, a rockable lever adapted to actuate the signal with one end, and a receptacle carried by the other end of the lever and effective when weighted to rock the lever and actuate the signal, and a frame carrying a buffer as a protector for 20 the appliance. 30
7. An infant's toilet appliance comprising an attachment for a toilet seat containing a signal device, an extension from the latter into the toilet zone, a rockable lever adapted to actuate the signal with one end, and a receptacle carried by the other end of the lever and effective when weighted to rock the lever and actuate the signal, and a vertical hollow shield opening from the extension 35 upon the toilet zone to serve as a splash guard. 35
8. In a device of the character described, the combination with a toilet receptacle, of a seat member associated with said toilet receptacle for sustaining an individual thereover in the required posture, signal means, and means operatively connected to said signal means to render said signal means responsive to the normal discharge of excrement to said toilet receptacle from a position above said seat member. 10
9. In a device of the character described, the combination with a toilet receptacle, of a seat member associated with said toilet receptacle for sustaining an individual thereover in a seated posture, signal means, and means operatively connected to said signal means and disposed within the confines of said toilet receptacle to render said signal means responsive to the normal discharge of excrement to said toilet receptacle from a position above said seat member. 15
10. In a device of the character described, the combination with a toilet receptacle, of a seat member detachably associated with said toilet receptacle for sustaining an individual thereover in the required posture, signal means attached to said seat member, and means operatively connected to said signal means to render said signal means responsive to the normal discharge of excrement to said toilet receptacle from a position above said seat member. 20
11. As an article of manufacture, a bracket member for attachment to a toilet seat, signal means associated with said bracket member, and signal operating means extending from said bracket member within the confines of the toilet seat to which it is intended for attachment so as to be in the general path of excrement descent and render said signal means operative in consequence thereof. 25 30 35
